UNITED STATES PATENT OFFICE.

JUAN G. MAZA, OF UPLAND, CALIFORNIA.

INDICATING MECHANISM FOR TYPEWRITERS.

Application filed July 9, 1928. Serial No. 291,151.

The present invention relates to improvements in typewriter attachments and has reference more particularly to a mechanism for indicating when the end of a page has been reached.

One of the important objects of the present invention is to provide an indicating mechanism that includes a means for setting an alarm to operate when a predetermined line on the page has been reached, an audible indicating means being provided to warn the typist that the last line to be typed on the page has been reached.

A further object is to provide an indicating mechanism that is adapted for association with the slideable carriage on which is mounted the platen roller, the indicating mechanism including an alarm actuating member that is cooperatively associated with one of the hand wheels associated with the ends of the platen roller.

Still a further object is to provide an indicating mechanism for typewriters of the above mentioned character which includes a means for normally rendering the audible alarm inoperative, said means being automatically released at a predetermined time whereby the alarm is actuated to indicate that the end of the page has been reached.

Still a further object is to provide an indicating mechanism for typewriters that can be readily and easily attached on a standard typewriter construction without necessitating any alterations of the typewriter, the indicating device being at all times positive and efficient in its operation.

A further object is to provide an indicating mechanism for typewriters which is simple in construction, inexpensive, strong and durable and further well adapted to the purpose for which it is designed.

Other objects and advantages of the invention will become apparent from the following description when taken in connection with the accompanying drawings.

In the accompanying drawings wherein like reference characters indicate corresponding parts throughout the same:

Figure 1 is a top plan view of the indicating mechanism embodying my invention showing the manner in which the same is attached on the platen roller carriage of a typewriter at one end thereof.

Figure 2 is a front elevation of the indi-

cating mechanism showing the same mounted on a typewriter.

Figure 3 is an end elevation thereof.

Figure 4 is a side elevation of the operating mechanism for the audible alarm, the casing being removed.

Figure 5 is a vertical sectional view taken approximately on the line 5—5 of Figure 4 looking in the direction of the arrows.

Figure 6 is a similar section taken on the line 6—6 of Figure 4 looking in the opposite direction.

Figure 7 is a similar section taken on the line 7—7 of Figure 4 looking in the same direction as the section taken on the line 6—6.

Figure 8 is a vertical sectional view taken approximately on the line 8—8 of Figure 4 looking in the direction of the arrows.

Figure 9 is a sectional view taken on the line 9—9 of Figure 7, looking downwardly.

Figure 10 is a sectional view taken on the line 10—10 of Figure 5, and

Figure 11 is a detail view of the attaching means for the bracket.

In the drawings wherein for the purpose of illustration is shown the preferred embodiment of my invention, the numeral 1 designates generally the platen roller of a standard typewriter that is secured on a suitable shaft 2 that extends through one end of the carriage 3, in the usual manner, said carriage being adapted for slideable movement on the typewriter in the manner also well known in the art.

The usual hand wheel that is secured on the projecting ends of the shaft 2 that carries the platen roller is illustrated at 4, and in the present instance secured on this hand wheel is the metallic band 5, the outer face of which is roughened for a purpose to be presently described.

The line spacing mechanism is not shown as the same forms no part of the present invention, and it is of course to be understood that the platen roller and hand wheel will rotate a certain distance each time the line spacing mechanism is actuated.

My improved indicating mechanism includes an arm 6 that is detachably secured at its inner end on the end of the carriage 3, through the medium of a bracket shown generally at 7. This bracket includes a vertical post 8 around which the inner end of the arm 6 which is notched engages and is

held thereon by means of the securing means shown at 9. Formed on the lower end of the vertical post 8 are the laterally extending feet 10 that rest upon the top of the end portion of the slidable carriage 3.

5 Depending from the post 8 at one side thereof is the stationary jaw 11, and cooperating with this stationary jaw is the movable vertically disposed jaw 12, said jaw engaging with the opposite sides of the end portion of the slidable carriage, as indicated in Figure 2.

10 The jaw 12 has extending transversely therethrough the screw 13, and this screw also passes through an opening disposed transversely in the lower end portion of the post 8.

15 The head of this screw engages with the outer face of the jaw 12 and threaded on the other end of the screw is the thumb nut 14 which is formed with an annular groove 15 in 20 the outer face of the hub portion thereof. Cooperating with this annular groove 15 is the yoke member 16 that is attached to the outer face of the stationary jaw 10, and this 25 structure provides a means whereby the thumb nut is maintained against the outer face of the jaw 11, and is prevented from moving with the screw, but upon turning the thumb nut, the jaw 12 carried by the headed 30 end of the screw will be moved toward or away from the stationary jaw depending upon the direction in which the thumb screw is rotated. A guide pin 17 extends laterally from the post 8 through an opening formed 35 in the upper end of the movable jaw to prevent rotation of said jaw, and this arrangement is clearly disclosed in Figure 2 of the drawings. In Figure 11, there is shown in detail the adjusting means for the jaws. In 40 this manner the bracket can be readily and easily secured or detached with respect to the slidable carriage 3.

45 Secured on the outer end of the arm 6 is the substantially semi-circular supporting strap 18, the inner end of this strap being associated with the outer end of the arm 6 in such a manner as to permit vertical swinging movement of the supporting strap when necessary, and a finger engaging portion 19 extends laterally from the free end of the strap 50 as disclosed more clearly in Figure 2. A spring tongue 20 is associated with the rear end of this strap 18 for cooperation with the outer end of the arm 6, as also disclosed very 55 clearly in Figure 3.

60 Removably supported by the semi-circular strap 18 is the circular casing 21, the outer side thereof being open, the cover for the open outer side of the casing constituting a cap shaped bell 22 which forms a salient part of the present indicating mechanism.

65 Arranged vertically within this casing 21 are the spaced discs 23, 24, 25, and 26, respectively, said discs being connected together in parallel spaced relation by any ap-

propriate securing means shown at 27. A bracket 28 is secured on the outer face of the disc 26 and carried by this bracket is a centrally located bolt 29, that projects through an opening formed centrally in the bell 22, 70 and a nut 30 is threaded on the outer end of this bolt to secure the bell in proper position with respect to the open outer side of the casing as clearly disclosed in Figure 1.

75 Adapted for cooperation with the bell 75 forming cap 22 is the striking head or hammer 31 that is secured or otherwise arranged on the lower end of a lever 32 that is pivoted adjacent its upper end on the outer side of the disc 26 as at 33, and the pivoted portion of this lever is formed with the dogs 34 and 35, respectively, as more clearly disclosed in Figure 5 for cooperation with the toothed wheel 36, secured on the outer end of a shaft 37 that extends through the disc 26, and also through a spring housing 38 arranged on the outer face of the disc 26 and located between the toothed wheel 36 and the disc 26, as more clearly shown in Figure 10.

80 A spring 39 is arranged in this housing 38 and is wound around the shaft 37, one end of the spring being secured to the shaft, while the other end is secured to the housing. A spur gear 40 is secured on the inner end portion of the shaft 37 for disposition adjacent 85 the inner side of the disc 26 as clearly illustrated in Figure 10, and this spur gear cooperates with the transverse teeth of the vertically sliding plunger 41 that is operable within a guide bracket 42 provided therefor on the inner face of the disc 26, it being understood of course that one side of the bracket is cut out to permit the spur gear 40 to mesh with the teeth of the sliding plunger as more clearly shown in Figure 6. The teeth of the plunger are designated by the numeral 43. 90

95 The plunger also projects upwardly through the top of the casing 21 and has arranged on its upper end a head 44 for moving the plunger downwardly whereby to actuate the shaft 37 to wind up the spring 39 for the purpose to be presently described.

100 For the purpose of holding the sliding plunger 41 in a lowered position whereby to lock the bell actuating hammer in an inoperative position, there is provided the latch 44 that is pivoted intermediate its ends on the inner face of the disc 26 as at 45, with reference more particularly to Figure 6. The lower end of this latch engages with the teeth 43 of the sliding plunger 41, and a spring 46 engages with the upper end of the latch to normally hold the lower end in operative engagement with the teeth 43 as also shown very 105 clearly in Figure 6.

110 The releasing means for the pivoted latch 44 comprises a horizontally disposed finger 47 formed from a relatively narrow strip of metal, and this finger extends through an opening 48 provided in the disc 25, the outer 115

end of said finger having engagement with the upper end of the latch 44. The inner end portion of this finger is pivotally supported on the bracket 49. In Figure 9 there is shown

5 a top plan view of this pivoted finger. This spring 46 will also hold the finger 47 in the position shown in Figure 9.

The actuating means for the finger whereby said finger will cause the latch to swing 10 away from engagement with the toothed plunger 41 comprises a pin 50 that extends radially from a shaft 51 which shaft is journaled through the discs 23, 24, and 25. The pin 50 is adapted to cooperate with the pivoted inner end of the finger in the manner to be presently described in detail.

Journaled for rotation through the innermost disc 23 at the bottom portion thereof is the shaft 52, and secured on one end of this 20 shaft is the socket member 53 with which is associated the wheel 54 that has frictional engagement with the roughened outer surface of the band 5 that is carried by the hand wheel associated with the adjacent end of the platen 25 roller supporting shaft 2. A spur gear 55 is secured on the other end of the shaft 52, and is disposed adjacent the inner face of the innermost disc 23. This spur gear meshes with the spur gear 56 secured on the end of the 30 shaft 51, and as is clearly shown in Figure 8, the spur gear 56 is considerably larger than the spur gear 55.

Also forming a salient part of the present invention is the settable wheel 57 that is secured on a shaft 58, which shaft extends through the disc 23 and is journaled at its end in the disc 24. A knurled or ribbed flange 59 is arranged on the outer edge portion of the wheel to facilitate easy rotation of the 35 same and the outer peripheral face of this wheel 57 is provided with the indicating graduations 60. The graduations are marked off in inches, and designate page lengths, that is to say the number of lines that may be 40 typed on a page, presuming of course that it is known how many lines there are to the inch. A stationary pointer 61 projects from the closed side of the casing 21 at the top thereof for cooperation with the graduations 60, as 45 clearly indicated in Figures 1 and 2.

A spur gear 62 is secured on the shaft 58 on which the settable wheel 57 is mounted and this spur gear 62 is arranged adjacent the inner face of the innermost disc 23, and has 50 meshing engagement with the relatively large spur gear 56, thus affording a positive connection between the shaft 52, and 58 with the intermediate shaft 51.

The operation of my improved indicating 55 mechanism may be briefly stated as follows. Initially the plunger 41 is in a raised position. The platen roller 1 is turned one-half a revolution in the reverse direction to which it is customarily turned, after which the 60 papers are put in as usual. The platen roller

is then turned in the right direction, and the top of the paper is spaced in the desired manner.

The thumb engaging portion 19 is grasped whereby to raise the indicating mechanism 70 upwardly so that the roller or wheel 54 will be moved out of engagement with the band 5.

The hand wheel 57 is then set by turning the same in the direction of the arrow until the desired page length is in alinement with 75 the pointer 61. The plunger 41 is then pressed downwardly so that the spring 39 will be wound up around the shaft 37 and the latch 44 will hold the plunger in its lowered position, as well as to maintain the spring 39 80 in a wound condition, the spring 46 maintaining the pivoted latch in its operative engagement with the toothed side of the plunger. The device is then lowered so that the roller 54 will be in engagement with the 85 band 5.

By moving the typewriter carriage to the right, the hand wheel 4 with the band 5 secured thereon will be turned a certain distance, and by reason of the roughened surface 90 of the band being in engagement with the roller 54, rotation will be imparted to said roller and its shaft 52, and this shaft by being geared up with the shaft 51 will rotate said shaft to move the pin 50.

When the end of the page has been reached, the shaft 51 will have been moved approximately a complete revolution so that the pin 50 which was initially disposed adjacent the rear side of the inner end of the pivoted finger 47 will now be positioned in front of the finger whereupon a further movement of the pin will cause the outer end portion of the pivoted finger 47 to press against the upper end of the latch 44, and this movement will result in the lower end of the latch being disengaged from the teeth 43 of the plunger 41. 95

This will cause the spring 39 to unwind, and operate the pivoted lever 32 through the medium of the toothed wheel 36 and the dogs 34 and 35 so that the hammer head 31 will intermittently strike the bell 22 and thus give an audible alarm to the typist that the end 100 of the page has been reached.

It will thus be seen from the foregoing description that I have provided an indicating mechanism for typewriters that will at all times be positive and efficient for indicating when the end of a page has been reached, 105 and due to its simplicity, the device can be readily installed on typewriter constructions of various makes without necessitating any alterations of the parts of the typewriter with which the present mechanism is to be 120 associated.

While I have shown the preferred embodiment of my invention, it is to be understood that minor changes in the size, shape and arrangement of parts may be resorted to 130

without departing from the spirit of the invention and the scope of the appended claims.

Having thus described the invention, what I claim as new is:—

5. 1. The combination with a typewriter including the platen roller, the usual hand wheel on each end of the roller for actuating the same, and the movable carriage for the roller; of means for actuating an audible alarm to indicate a page end, said means including a casing supported on the carriage, a bell carried by the casing, a striking hammer for the bell to sound an alarm, spring operating means for actuating the hammer, 10 a member operable to wind said spring, a latch for holding the spring in a wound condition, and means operable by said hand wheel for releasing the latch to effect the actuation of the hammer, and sound an alarm 15 when a page end is reached, and manually operable means for setting said releasing mechanism.
2. The combination with a typewriter including a platen roller, the usual hand wheel on each end of the roller for actuating the same, and the movable carriage for the roller, of a casing mounted on the end of the carriage, a bell carried by the casing, a striking hammer for the bell, spring controlled means 20 for actuating the hammer, mechanism for winding up the spring, a pivoted latch associated with the mechanism to hold the spring in a wound condition, means operable by the hand wheel for releasing said latch, and automatically effecting the actuation of the striking hammer to sound an alarm to indicate a page end, and manually settable means for positioning said releasing means.
3. The combination with a typewriter including the platen roller, the usual hand wheel on each end of the roller for actuating the same, and a movable carriage for the roller; of a casing supported on one end of the 25 slidable carriage, a bell carried by the casing, a striking hammer for said bell, spring controlled means for actuating the striking hammer, mechanism for winding the spring, a pivoted latch for cooperation with said mechanism to hold the spring in a wound condition, a pivoted finger arranged in the casing for cooperation with the latch to move the same to an inoperative position and automatically effect the actuation of the striking hammer to sound an alarm when a 30 page end is reached, a shaft carried by the casing, a roller on the shaft for engagement with the hand wheel to rotate therewith, an additional shaft journaled for rotation in the casing, intermeshing gears between said shafts, a pin carried by said additional shaft for actuating said finger, and manually settable means for positioning said pin initially with respect to the finger.
4. The combination with a typewriter including the platen roller, the usual hand wheel on each end of the roller for actuating the same, and a movable carriage for the roller; of a casing supported on one end of the 35 slidable carriage, a bell carried by the casing, a striking hammer for said bell, spring controlled means for actuating the striking hammer, mechanism for winding the spring, a pivoted latch for cooperation with said mechanism to hold the spring in a wound condition, a pivoted finger arranged in the casing for cooperation with the latch to move the same to an inoperative position and automatically effect the actuation of the striking hammer to sound an alarm when a 40 page end is reached, a shaft carried by the casing, a roller on the shaft for engagement with the hand wheel to rotate therewith, an additional shaft journaled for rotation in the casing, intermeshing gears between said shafts, a pin carried by said additional shaft for actuating said finger, and manually settable means for positioning said pin initially with respect to the finger, said last mentioned means comprising a shaft journaled through one side of the casing, a graduated wheel secured on said shaft, a pointer on the casing 45 for cooperation with the graduations on the wheel, and intermeshing gears carried by the last mentioned shaft and the pin carrying shaft.
5. The combination with a typewriter including the platen roller, the usual hand wheel on each end of the roller for actuating the same, and a movable carriage for the roller; of a casing supported on one end of the 50 slidable carriage, a bell carried by the casing, a striking hammer for said bell, spring controlled means for actuating the striking hammer, mechanism for winding the spring, a pivoted latch for cooperation with said mechanism to hold the spring in a wound condition, a pivoted finger arranged in the casing for cooperation with the latch to move the same to an inoperative position and automatically effect the actuation of the striking hammer to sound an alarm when a 55 page end is reached, a shaft carried by the casing, a roller on the shaft for engagement with the hand wheel to rotate therewith, a member operable by said shaft for engagement with the finger to actuate the same, and manually settable means for controlling the 60 period when said member will actuate the finger.
6. The combination with a typewriter including the platen roller, the usual hand wheel on each end of the roller for actuating the same, and a movable carriage for the roller; of a casing supported on one end of the 65 slidable carriage, a bell carried by the casing, a striking hammer for said bell, spring controlled means for actuating the striking hammer, mechanism for winding the spring, a pivoted latch for cooperation with said mechanism to hold the spring in a wound condition, a pivoted finger arranged in the casing for cooperation with the latch to move the same to an inoperative position and automatically effect the actuation of the striking hammer to sound an alarm when a page end is reached, a shaft carried by the casing, a roller on the shaft for engagement with the hand wheel to rotate therewith, an additional shaft journaled for rotation in the casing, intermeshing gears between said shafts, a pin carried by said additional shaft for actuating said finger, and manually settable means for positioning said pin initially with respect to the finger.

condition, a pivoted finger arranged in the casing for cooperation with the latch to move the same to an inoperative position and automatically effect the actuation of the striking hammer to sound an alarm when a page end is reached, a shaft carried by the casing, a roller on the shaft for engagement with the hand wheel to rotate therewith, a member operable by said shaft for engagement with the finger to actuate the same, 10 manually settable means for controlling the period when said member will actuate the finger, and means for forcibly moving the roller out of engagement with the hand wheel. In testimony whereof I affix my signature.

JUAN G. MAZA.
